ELECTRICAL FIXTURE SUPPORT AND CONNECTOR

Edward L. Zientowski and Lucille H. Williams,
Toledo, Ohio

Application March 27, 1951, Serial No. 217,720

3 Claims. (Cl. 174—54)

1

This invention relates to a combined electrical fixture support and connector and more especially to an arrangement for connecting and supporting lighting fixtures or other electrical devices particularly of the character adapted to be secured to a wall or ceiling. It has been conventional practice to support lighting fixtures from ceilings and walls by means of rods and connections of a character requiring the use of tools for disconnecting or dismantling the fixtures for purposes of cleaning or for the purpose of interchanging fixtures. Moreover, the electrical connections of the fixtures are usually intertwined and in some instances soldered or otherwise secured to the wires or conductors of the current supply. Thus heretofore, in order to remove a lighting fixture for cleaning or interchangeability, it was necessary to either untwist the wires providing the electrical connection or cut them in order to clean or effect an interchange of fixtures. It has been a laborious task to disconnect and clean lighting fixtures supported or mounted in the manner above mentioned.

The present invention embraces a combined electrical fixture support and electrical circuit connector arranged whereby the fixture is removably secured to a support and the electrical or current connection made through the use of a readily disconnectable plug and socket device.

An object of the invention resides in the provision of a combined fixture support and circuit connector of a character which may be interchanged with conventional fixture supporting means without necessitating any modification or change in the supporting ceiling or wall or the current conducting means.

Another object of the invention is the provision of a lighting fixture support and connector wherein the lighting fixture is mechanically connected to the support through readily disconnectable means which may be manipulated without the use of tools and the electrical circuit connection established to the illuminating means or other current consuming devices by a manually removable and connectable plug and socket arrangement.

Another object of the invention resides in a combined fixture outlet or connection box equipped with a socket connection which facilitates the establishment of an electrical circuit with a current supply line or cable with a minimum of effort through the use of a manually insertable plug element.

Another object of the invention resides in an

arrangement for connecting a depending lighting fixture or the like with a supporting means wherein the fixture may be quickly and easily removed for purposes of cleaning or for interchangeability with other fixtures without the use of tools.

A further object of the invention resides in the provision of a combined fixture support and connector which is adapted to accommodate various types and kinds of fixtures without necessitating changes in the mounting wall or ceiling or the electrical current supply line.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure 1 is a fragmentary isometric view illustrating a portion of a conventional ceiling construction with the combined fixture support and connector installed therewith and illustrating a fixture connected thereto;

Figure 2 is a vertical sectional view through the fixture support and connector of our invention illustrating a part of the lighting fixture arrangement connected thereto, and

Figure 3 is a bottom plan view of the combined fixture support and connector with the cover installed.

While we have illustrated the arrangement of our invention as utilized with a lighting fixture of the depending type, it is to be understood that we contemplate the use of the arrangement of our invention with any type of fixture mounted on any type of supporting surface.

Referring to the drawings in detail and first to Figures 1 and 2, there is illustrated a preferred arrangement of the invention in conjunction with a ceiling construction in which the joists are indicated at 10 to which is secured the lath or plaster board 12 provided with a coating of plaster 14 or other covering or finishing material. Secured between adjacent joists is a strap or bar 16 connected to the joists by means of screws 17 or other suitable means.

Disposed adjacent and beneath the central portion of the bar 16 is a housing or fixture outlet box 18 which may be of substantially rectangular configuration or other shape if desired. The box 18 in its normal position of installation in

a ceiling support is inverted with its rear or bottom wall 19 coextensively disposed in contact with the strap 16 as particularly shown in Figure 2. As illustrated in the drawings, the arrangement is particularly adapted to support a lighting fixture 20 to which is connected a series of interconnected links 21 forming a chain, the upper link engaging in an eye 23 formed on a fitting 24. The fitting 24 is integrally provided with an upwardly extending hook-like portion 26 which is adapted for interlocking or hooked engagement with a hook-like portion 28 formed on a fitting 29. The fitting 29 is fashioned with a cylindrical portion 30 interiorly threaded to accommodate a rod or element 32, the latter having at its upper end a threaded portion 34 which is adapted to extend through registering openings formed in the center of the outlet box 18 and the strap 16.

The element 32 is provided with a flange 36 which engages the lower surface of the bottom wall 19 of the outlet box to position the element therein, a lock nut 38 being threaded upon the portion 34 to fixedly secure the element 32 to the box 18. The fitting 24 is formed with a threaded tenon portion 42 which accommodates an escutcheon 44 having a bead 45 adapted to engage the ceiling or wall surface to present a finished appearance and to enclose the fittings 26 and 28. The escutcheon 44 is held in place on the fitting 24 by means of a nut 46 which may be manipulated manually to hold the escutcheon in position.

The position of the fixture 20 may be adjusted by disconnecting the hook-like portions 26 and 28 and threading the fitting 29 on the rod 32 until the proper distance of the fixture position below the ceiling is secured.

The outlet box or housing 18 is provided with an opening 50 adapted to receive current conducting wires 54 and 55 sheathed in a metal casing 52 for conducting electrical current into the box 18. Disposed adjacent a vertical or side wall of the box 18 is a female connector or socket 58 provided with terminals 59, one of which is shown in Figure 2, adapted to receive the wires 54 and 55 for supplying current to the socket 58. Secured to the rear face of the socket 58 is an L-shaped bracket 60 having a horizontal portion 61 secured to the socket 58 by means of rivets 62, the upwardly extending portion 64 of the bracket being secured to the box 18 by means of a rivet 65 or other suitable securing means. In this manner the socket 58 is fixedly mounted in outlet box 18. The lower or obverse surface 68 of the socket is disposed in parallelism with a cover member 70 for the outlet box 18, the cover member being secured thereto by means of screws 72 and 73 in the conventional manner, the screw 72 forming a pivotal axis for the cover 70, the cover being provided with a slot 74 of a dimension sufficient to accommodate the head of the screw 73 for removing the cover without completely disengaging the screws from the box. The box 18 is formed with integral inwardly projecting ears 75 formed with threaded openings to accommodate the screws 72 and 73. The cover 70 is provided with a circular opening 71 through which the forward portion of the socket 58 is extended in the manner shown in Figures 2 and 3.

The electrically energizable illuminating means (not shown) or other current consuming means of the fixture 20 is connected with a pair of conductors or wires 79 and 80 for conducting current to the current consuming means. The conductors

79 and 80 are connected with a male fitting or plug 82 provided with contacts or prongs 83 and 84 which are adapted to be interjected into receptacle openings 86 and 87 formed in the socket 58 into engagement with contacts (not shown) and when inserted therein in the position indicated in Figure 2 establish a circuit with the conductors 54 and 55. The plug member 82 is readily removable by exerting manual downward force upon the plug withdrawing the prongs 83 and 84 from the receptacles 86 and 87 to effect a disengagement or interruption of the circuit between the line or current feed conductors 54 and 55 and the conductors 79 and 80 leading to the current consuming element of the fixture.

In the event it is desired to disconnect the lighting fixture for purposes of cleaning or to insert a different fixture in its place, the following steps completely disconnect the fixture and the current conducting means. The nut 46 is backed off of the threaded tenon 42 permitting the escutcheon 44 to be dropped from engagement with the ceiling or wall surface. The hook 26 may then be manually disconnected from the hook 28 and the plug 82 manually withdrawn from engagement with the socket 58 to effect a complete disconnection of the circuit establishing means with the current consuming element of the fixture. After the plug 82 is withdrawn the entire fixture including the fitting 24, escutcheon 44 and the plug 82 may be readily removed from the ceiling or other support without involving the use of any tools. Furthermore this may be accomplished in a very short period of time. When it is desired to replace or reconnect the fixture, the user first inserts the plug 82 into the socket 58 and rehooks the portion 26 with portion 28, the escutcheon 44 is moved upwardly to the position shown in Figure 2 and the nut 46 rethreaded upon the tenon 42 until it engages the escutcheon 44 to hold the latter in a position where the beading or edge position 45 is in contact with the ceiling or other support. In this manner the fixture may be installed in a short period of time and a circuit reestablished to the current consuming means of the fixture without the use of any tools.

If desired the cover member 70 for the box 18 may be dispensed with where the escutcheon 44 is of a character to completely mask the box, socket connection and fixture connecting elements. In installations where an escutcheon is not used, the cover 70 may be employed to advantage not only for the purpose of improving the appearance of the assembly but also to protect the circuit connections and socket contained in the outlet box.

It is important that, within the scope of the invention, modifications and different arrangements may be made other than is herein disclosed, and the present disclosure is illustrative merely, the invention comprehending all variations thereof.

What we claim is:

1. In combination with a lighting fixture of a type adapted to depend from a supporting surface, an outlet box adapted to accommodate electrical current supply conductors, a socket disposed within said box, a bracket securing said socket to a wall of said box, said socket having terminals adapted to be connected to the supply conductors, a rod having a flange, said box having an opening formed in a wall thereof, one end of said rod passing through said opening so as to engage said flange at said opening with an inner wall of said box, means securing said one end to

said box, a hook member adjustably mounted upon the other end of said rod, a second hook member supporting said fixture for interengagement with said first mentioned hook member and having a flange thereon and a central opening therein, an escutcheon engaging said flange, removable means mounted on said second hook member securing said escutcheon to said second hook member, a conductor extending into the escutcheon and passing through said central passage of said second hook member, and a manually removable and placeable plug on the inner end of said conductor cooperating with said socket for establishing an electrical circuit to said fixture.

2. In combination with a lighting fixture of a type adapted to depend from a supporting surface, an outlet box adapted to accommodate electrical current supply conductors, a socket disposed within said box, a bracket securing said socket to a wall of said box, said socket having terminals adapted to be connected to the supply conductors, a rod threaded at either end having a flange located between said threaded ends, said box having an opening formed in a wall thereof, one end of said rod passing through said opening so as to engage said flange at said opening with an inner wall of said box, a locknut threaded on said one end securing said rod to said box, a threaded hook member adjustably mounted upon the other threaded end of the rod, a second threaded hook member supporting said fixture for interengagement with said first mentioned hook member and having a flange thereon and a central passage therein, an escutcheon engaging said flange, removable means mounted on said second threaded hook member securing said escutcheon to said second threaded hook member, a conductor extending into the escutcheon and passing through said central passage of said second threaded hook member, and a manually removable and placeable plug on the inner end of said conductor cooperating with said socket for establishing an electrical circuit to said fixture.

3. In combination with a lighting fixture of a type adapted to depend from a supporting sur-

face, an outlet box adapted to accommodate electrical current supply conductors, a socket disposed within said box, a bracket securing said socket to a wall of said box, said socket having terminals adapted to be connected to the supply conductors, a strap secured to said supporting surface having a hole therein, a rod threaded at either end having a flange located between said threaded ends, said box having an opening formed in a wall thereof, one end of said rod passing through said opening and said hole so as to engage said flange at said opening with an inner wall of said box, a locknut threaded on said one end securing said rod to said box and said strap, a threaded hook member adjustably mounted upon the other threaded end of the rod, a second threaded hook member supporting said fixture for interengagement with said first mentioned hook member and having a flange thereon and a central passage therein, an escutcheon engaging said flange, removable means mounted on said second threaded hook member securing said escutcheon to said second threaded hook member, a conductor extending into the escutcheon and passing through said central passage of said second threaded hook member, and a manually removable and placeable plug on the inner end of said conductor cooperating with said socket for establishing an electrical circuit to said fixture.
